UNITED STATES PATENT OFFICE

134,272

DESIGN FOR A TEXTILE FABRIC OR SIMILAR ARTICLE

Robert E. Fatherley, Darien, Conn., and Herbert
P. Blumberg, New York, N. Y., assignors to Cohn-Hall-Marx Co., New York, N. Y.

Application October 9, 1942, Serial No. 108,480

Term of patent 3½ years

To all whom it may concern:

Be it known that we, Robert E. Fatherley and Herbert P. Blumberg, both citizens of the United States of America, residing at Point-O-Woods Road, Darien, Connecticut, and 320 Central Park West, New York, New York, respectively, have invented a new, original, and ornamental Design for a Textile Fabric or Similar Article, of which the following is a specification, reference being had to the accompanying drawing, forming a part thereof.

The figure is a plan view of a textile fabric showing the complete width of our design. The dot and dash lines on the drawing outline substantially the design unit, which unit is repeated in regular succession as indicated by the extensions beyond the unit boundaries.

We claim:

The ornamental design for a textile fabric or similar article, as shown and described.

ROBERT E. FATHERLEY.
HERBERT P. BLUMBERG.
